John J. Lubberts and Lambert J. Mulder, Grand Rapids, Mich., assignors to Thomasville Chair Company, Thomasville, N. C., a corporation of North Carolina

Application July 11, 1957, Serial No. 46,904

Term of patent 7 years

(Cl. D33—14)

FIG. 1.

FIG. 2

FIG. 3.

Figure 1 is a perspective view of a table embodying our new design;

Figure 2 is a top plan view; and

Figure 3 is a sectional view taken along lines 3—3 of Figure 1.

The dominant features of our design reside in the combination on the table disclosed of the hexagonally shaped legs, the specific top, and the spaced metallic decorations, all as shown.

We claim:

The ornamental design for table, substantially as shown, and described.
